UNITED STATES PATENT OFFICE.

VIRGIL G. SKEEN, OF WICHITA FALLS, TEXAS.

CULTIVATOR.

SPECIFICATION forming part of Letters Patent No. 674,481, dated May 21, 1901.

Application filed January 31, 1901. Serial No. 45,462. (No model.)

To all whom it may concern:

Be it known that I, VIRGIL G. SKEEN, a citizen of the United States, residing at Wichita Falls, in the county of Wichita and State of Texas, have invented certain new and useful Improvements in Cultivators; and I do declare the following to be a full, clear, and exact description of the invention, such as will enable others skilled in the art to which it applies to make and use the same.

My invention relates to improvements in cultivators.

The objects of the invention are, first, to provide swiveled carrying-wheels which are under the direct control of the driver or operator and may be turned at an angle to the line of draft to guide the machine, while at the same time maintaining the plows in proper position with reference to each other to the center of the frame and to the drill or row, thus preventing the plows from sliding off laterally and cutting too deeply at some points and skipping others, particularly on making a turn or cultivating curved rows, whereby uniformity of cultivation is insured; second, to provide a swiveled wheel attachment which may be applied to cultivators already in use; third, to provide an attachment of this character adapted for walking or riding cultivators, and, finally, to generally simplify and improve the construction and increase the practical efficiency of cultivators of this character.

With these and other objects in view, which will appear as the nature of the invention is better understood, the invention consists of certain novel features of construction, combination, and arrangement of parts, as will be hereinafter more fully described, and particularly pointed out in the appended claims.

In the accompanying drawings, Figure 1 is a view in side elevation, of a cultivator embodying my invention. Fig. 2 is a top plan view thereof. Fig. 3 is a rear end elevation. Fig. 4 is an enlarged detail perspective view of the beam and coöperating parts constituting my invention.

Like reference characters designate corresponding parts throughout the several views. A in the drawings represents the main transverse frame-beam of the cultivator, B the tongue or pole, C braces connecting the

tongue to said beam, D a supporting-yoke supported by said tongue and braces and having lateral arms d, E braces connecting said arms to the beam A, F the seat-supporting frame, G the doubletree or draft attachment, and H and I sets of links connecting the doubletree to the arms d, all of which parts are embodied in cultivators now in common use. The parallel plow-beams 1 are also embodied in prior machines, but are constructed and mounted in a novel manner in my attachment, and hence constitute part of my invention.

In accordance with my invention the carrying-wheels 2 are mounted upon stub-axes 3, connected to vertical shafts 4, swiveled in bearing-brackets 5 upon the ends of the beam A, which shafts are provided at their lower ends with right-angular and forwardly-extending foot portions 6. Through these foot portions and through the projecting upper ends of the shafts project substantially L-shaped bolts 7, which are provided at their upper and lower ends with securing-nuts 8 and 9 and serve to hold the said shafts in place and to brace said foot portions 6. By this construction it will be seen that the wheels 2 are swiveled to swing in arcs of circles in a plane parallel with the beams 1 to vary their angular position relative thereto.

The plow-beams 1 are pivotally connected at their forward ends, by means of bolts 10, to swiveled brackets or eyes 11 on the arms d of the frame-yoke D, which bolts 10 are each adapted to engage one of a series of openings 12, formed in said brackets, whereby the beams are not only adapted to swing vertically to compensate for a yielding motion of the plows on striking an obstruction, but are also adapted to swing in a direction transversely of the cultivator. The two beams are connected by means of a transverse yoke 14, having arms 15, provided with series of openings 16 to receive the coupling pins or clips 17 on said beams, whereby the beams are also connected to said yoke so as to be adjusted toward and from each other. In advance of the yoke the beams are further connected to the bolts 7 by links 18, whereby they are adapted to communicate motion to and swing simultaneously with the wheels. Each of these links 18 is adjustable as to

length, being composed of two sections having overlapping meeting ends united by bolts 18^a, so as to be adjusted to compensate for the adjustment of the beams 1 relatively to 5 each other and to the said bolts 7. Stirrups or foot-rests 19 are arranged upon the beams 1 below and a short distance in advance of the driver's seat. To enable the driver to swing the beams and wheels from his seat, I 10 connect the bolts 7 by means of a bar 22, which is adapted to be operated by a lever 23, pivoted at its forward end to the rear extremity of the tongue B and provided at its 15 rear end with a handle located so as to be readily accessible to the driver from his seat. By swinging this lever to one side or the other the wheels and beams may be turned in either direction in an obvious manner. The lever is held rigidly in position by a pawl 20 thereon engaging a rack 24 on the main transverse beam A. If the cultivator be of the walking type, the beams may be provided with handles 20 for a similar purpose. To lock the beams and wheels rigidly against 25 movement, pivoted bolts 26 are provided and have hooked ends 27 to engage the horizontal portions of the connecting bolts or rods 7.

Each beam 1 carries plows 21 and may coöperate with the other to support a central drill, 30 (not shown,) according to the character of work to be done. Suitable levers 28 and connections are provided for elevating the said beams, and other operating devices may be arranged at points needed.

35 The parts shown in Fig. 4, with the exception of the beams 1, constitute an attachment which may be applied to existing machines which it is desired to equip with the invention.

The following advantages are secured by 40 the use of my invention: The beams 1 can be guided to maintain the plows on either side of the rows or drill equidistant the one from the other and as near the row or drill as may be necessary for uniform and equal 45 cultivation. In other words, the swiveled wheels and beam may be swung so as to always keep the center of the cultivator over the drill or row and prevent the plows from cutting too much in one place and skipping 50 another and from sliding off in a direction laterally of the row. The plows are also under the complete control of the driver or follower, as the cultivator is guided mainly by the beams instead of the tongue. The wheels 55 are, furthermore, maintained equidistant from the drill or row, the use of a parallel movement obviated, as the beams are always equidistant from the drill and from each other, and the cultivator may be made to approach a fence or other obstruction much closer than cultivators of the usual construction.

The improvement is, in addition, a great advantage in turning or cultivating a curved 65 row, for the above-noted and other obvious reasons.

From the foregoing description, taken in

connection with the accompanying drawings, the construction, mode of operation, and advantages of my invention will be readily understood without an extended description. 70

While the preferred embodiment of the invention is as herein disclosed, it will of course be understood that changes in the form, proportion, and minor details of construction may be made within the scope of the invention without departing from the spirit or sacrificing any of the advantages thereof. 75

Having thus fully described my invention, 80 what I claim as new and useful, and desire to secure by Letters Patent of the United States, is—

1. In a cultivator, the combination of a main frame-beam, swiveled plow-beams, 85 swiveled shafts upon the main beam, carrying-wheels mounted upon said shafts, and adjustable links connecting the shafts and plow-beams so as to impart a positive movement to each plow-beam upon the swinging of said shafts, substantially as described. 90

2. In a cultivator, the combination of a main frame-beam, horizontally-swinging plow-beams, vertical shafts swiveled to the main beam, carrying-wheels mounted upon 95 said shafts, and links adjustably connecting the shafts to the plow-beams, each of said links being composed of overlapping parts adjustably connected, substantially as described. 100

3. In a cultivator, the combination of a main frame-beam provided with bearings, vertical shafts swiveled in said bearings, carrying-wheels mounted upon said shafts, horizontally-swinging plow-beams, and adjustable links connecting directly between said shafts and the plow-beams so as to impart a positive movement to each beam upon the movement of the shafts, substantially as described. 105

4. In a cultivator, the combination of a main frame-beam provided with bearings, vertical shafts swiveled in said bearings and provided with stub-axles and projecting foot portions, bolts connecting the upper end of each shaft with its foot portion, carrier-wheels mounted upon the stub-axles, horizontally-swinging plow-beams, and links connecting between said bolts and the plow-beams, substantially as described. 115

5. In a cultivator, the combination of a main frame-beam, a supporting-yoke provided with lateral arms, horizontally-swinging plow-beams adjustably connected to said lateral arms, vertical shafts swiveled upon 125 the main frame-beam, carrying-wheels mounted upon said shafts, and adjustable links connecting the shafts with the plow-beam, substantially as described.

6. In a cultivator, the combination of a main frame-beam provided with bearings, vertical shafts swiveled in said bearings and provided with laterally-projecting stub-axles and forwardly-projecting foot portions, L- 130

shaped bolts connecting the upper end of each vertical shaft with its foot portion, carrier-wheels mounted upon the stub-axles, horizontally-swinging plow-beams, and adjustable links connecting the bolt of each shaft with the adjacent plow-beam, substantially as described.

7. In a cultivator, the combination of a main frame-beam provided with bearings, vertical shafts swiveled in said bearings and provided with laterally-projecting stub-axles and forwardly-projecting foot portions, L-shaped bolts connecting the upper ends of the shafts with the foot portions thereof, horizontally-swinging plow-beams, links connecting the same with said bolts, a bar connecting the bolts, and an operating-lever for moving the bar to swing the bolts and shafts, substantially as described.
8. In a cultivator, the combination of a main frame-beam, vertical shafts swiveled upon the beam and provided with laterally-extending stub-axles and forwardly-projecting foot portions, an L-shaped bolt connecting the upper end of each shaft with its foot

portion, carrier-wheels mounted upon the stub-axles, a supporting-yoke provided with laterally-extending arms, plow-beams mounted to swing in a horizontal plane and adjustably connected to said arms, and links adjustably connecting the bolt of each shaft with the adjacent plow-beam, substantially as described.

9. An attachment for cultivators comprising bearing-brackets adapted to be connected to the main frame-beam of the cultivator, vertical shafts mounted in said brackets and provided with stub-axles and foot portions, a bolt connecting the upper end of each shaft with its foot portion, and adjustable links for connecting the bolts of the shafts with swinging plow-beams, substantially as described.

In testimony whereof I have hereunto set my hand in presence of two subscribing witnesses.
